UNITED STATES PATENT OFFICE.

LEONORE C. HILL, OF BETHESDA, MARYLAND

COMBINED CLOTHING HANGER AND PROTECTOR.

1,078,729.

Specification of Letters Patent. Patented Nov. 18, 1913.

Application filed January 7, 1913. Serial No. 740,669.

To all whom it may concern:

Be it known, that I, LEONORE C. HILL, a citizen of the United States, residing at Bethesda, in the county of Montgomery and State of Maryland, have invented certain new and useful Improvements in Combined Clothing Hangers and Protectors; and I do hereby declare the following to be a full, clear, and exact description of the invention, such as will enable others skilled in the art to which it appertains to make and use the same.

This invention relates to wardrobes, and it more particularly relates to an improved form of combined clothing hanger and protector.

An object of the present invention is to provide a rack or hanger whereon the maximum number of clothing articles may be supported within a minimum space, consistent with the proper care and preservation of said clothing.

Another object of the invention is to provide a hanger of this character which constitutes a protecting cover for the clothing, and to provide an improved clamping element for the protecting cover, whereby the latter may be easily removed and replaced, when necessary, for cleaning or renewing the cover, or for transportation.

Another object of the invention is to provide a device of this character which may be located within a comparatively small closet or cupboard, or in the corner of a room, and which may be rotated, for bringing the articles of clothing successively into position for being easily reached by the proper person.

A still further object of the invention is to provide a hanger of this character which may be secured onto a closet door and to be swung laterally with relation to the door, so that the hanger may be properly located at the most convenient portion of the closet when the door is closed.

Another object of the invention is to provide a general utility rack of this character which is adapted to be located either in a hall or in a private apartment; and which is of symmetrical and ornamental outline, and withal, comparatively light, convenient, comparatively inexpensive and thoroughly efficient.

Other objects and advantages may be recited hereinafter and in the claims.

In the accompanying drawings, which supplement this specification, Figure 1 is a perspective view illustrating a closet door and my improved clothing hanger and protector supported by the door. Fig. 2 is an enlarged vertical sectional view through the upper portion of the cover and through the hanger. Fig. 3 is an elevation view, illustrating a somewhat modified form of the invention. Figs. 4, 5 and 8 illustrate other modified forms, and, Figs. 6 and 7 are detail views of the structure indicated by like reference numerals in Fig. 3; Fig. 7 being an enlarged sectional view taken on the line 7—7 of Fig. 6.

In these drawings, in which similar reference characters correspond with similar parts, throughout the several views; the hanger consists of a stationary bracket or anchor member 10, (see Figs. 1 and 2), a movable arm or bracket 11, a depending rod 12, a rotary element or wheel 13 and hooks 14. The anchor member 10 is secured to the door 15 of a closet 16, while the bracket or arm 11 is pivotally connected to the member 10 by means of a pivot pin 17. The depending rod 12 constitutes a support for the wheel 13, being pivotally connected to said wheel and to the free end of the bracket 11; the latter being apertured at 18, so as to form a bearing for the upper end of said rod 12. The upper end of said rod is provided with screw-threads onto which are fitted a lower thumb-nut 19 and an upper thumb-nut 20, these nuts being knurled, as illustrated. The aperture 18 is not screw-threaded, and so, the rod 12 may rotate freely therein when the nuts 19 and 20 are not tightened against the bracket 11, but when so tightened, the hanger is held against accidental rotation, which might occur in consequence of a draft of wind, etc. The nut 20 may be easily removed, when desired, for separating the elements of the rack for transportation, but if the rack is rotated in the proper direction, at all times, there is no danger of the nut becoming accidentally disengaged from the rod 12.

The rod 12 is provided with an enlargement or shoulder 21 onto which is seated the

lower clamping element 22 which coacts with a somewhat similar upper clamping element 23, and these clamping elements together with the rod 12 and the nut 19 constitute a clamp, between the annular clamping jaws of which is secured a protecting cloth or cover 24. The upper edge of this cover is gathered into plaits or folds, and thereby caused to converge to such a degree that said upper edge may be inserted and clamped between the hemispherical clamping elements 22 and 23, the nut 19 coacting with the rod 12 for forcing said clamping elements tightly against the said upper edge of the protecting cover.

In Fig. 1, the vertical edges of the cover 24 are illustrated as being separated, or in proper position for removing an article of clothing from the hanger, but it is obvious that said vertical edges may be brought into lapped relation, so as to entirely surround and protect the clothing.

As previously intimated, the rod 12 may be rotated in the bearing 18, while the wheel 13 may be rotated on the rod, the latter being held stationary, either by means of the nut 20 or otherwise; and so, by holding the cover 24 with one hand, the hanger may be rotated with relation to the cover, so as to bring any article of clothing supported thereby in front of the opening between the vertical edges of the cover.

In the modifications shown in Figs. 3 and 4, the nut 20 may be dispensed with, the head 20' being securely fixed on the rod 12' and 12^a, respectively, and in these modifications, I may provide a collar 21' which may be slid up and down on the rod, so as to allow the cover to be inserted between the clamping elements, and any proper means, such as indicated at 21^a may be employed for securing the collar in its upper position, whereupon, the knurled nut 19 may be operated for tightening the clamp, as previously described. In the modification shown in Fig. 3, an anchor member 10' is secured on the ceiling of a room while in lieu of the wheel 13, which may be of tubular cross section, I may employ a hanger ring 13' having hooks 14' formed thereon, and in practice, a ring of this kind would be stamped from sheet metal, together with the hooks 14' and with apertured ears 13^a to which are secured supporting-chains 13^b, the latter depending from a spider or hub 13^c which is pivoted on the lower end of the rod 12'. This form of hanger is obviously very convenient, as it may be easily packed for transportation into small space, without the necessity for disconnecting any of the elements by collapsing the cover and the flexible elements 13^b, in an obvious manner.

As illustrated in Figs. 6 and 7, the member 13' may be stamped from a sheet of metal, and the blank, which is produced by

stamping, may then be formed with an annular flange 14^a from which the hooks 14' depend, while the ears 13^a may be struck up from the sheet metal, or else, the members 13' and 14^a may be formed separately, and afterward united at 13^a.

The supporting arm or bracket 11', illustrated in Fig. 4, is provided with a screw-clamp 11^a whereby it may be secured onto a shelf or the like. This form is especially convenient because of the lack of necessity for a screw driver or other tool, in mounting the hanger.

The modified form illustrated in Fig. 5 is especially applicable for use in halls or corridors, as it includes an umbrella rack or stand and a hat rack, together with the hanger ring 13 and hooks 14. The hat rack 25 is preferably supported above the clothes hanger, and comprises a series of relatively long arms 26 which are curved outwardly and upwardly, so that they extend a sufficient distance into a hat, supported thereby, to avoid any reasonable probability of the hat being accidentally dislodged therefrom. The umbrella stand consists of a ring 27 supported by the vertical support or rod 28 which supports the hat rack and the clothing hanger, and under this ring 27 is a bowl or drip pan 29 which constitutes a portion of the base 30. This base is preferably made of cast iron, brass or other suitable metal, so that the weight thereof is sufficient to retain the device in vertical position, even when excessive weight of the clothing tends to cause it to topple. The base 30 is also formed with a socket 31 in which the support or standard 28 is seated, and moreover, the base is provided with a chamber, under the bowl 29, and into this chamber is fitted a drawer 32, for receiving the water which drips from the umbrellas and which passes through the apertures 33 which communicate with the bowl and with the chamber thereunder.

In the modified form illustrated in Fig. 8, the structure is similar to that of Fig. 3, the principal difference consisting in the means by which the hanger is mounted. In this figure, the rod 12 is replaced by a supporting member 12^b consisting of an internally screw-threaded element 12^c which engages the threads of a lower supporting element or rod which has its upper end screw-threaded at 12^d. The member 12^b is formed with an eye 12^e which is adapted to engage with a nail, hook or other proper support, as for instance, the arm or bracket 11^b. By proper manipulation of the members 12^b and 12^c, the clamping elements 22 and 23 may be actuated in the manner previously described.

This hanger may have its several elements formed from any suitable metal, and all of the parts should be formed neatly and be

plated and polished so that it will present an attractive appearance, which will combine with the obvious advantages described in the foregoing, for rendering the device desirable from every standpoint.

It will be seen that I have provided a device of this character which is thoroughly capable of attaining the foregoing objects, and in a practical and efficient manner.

I do not limit my invention to the exact details of construction, combination and arrangement of parts, as herewith illustrated and described, but my invention may only be limited by a reasonable interpretation of the claims.

I claim:

1. A clothes hanger and protector consisting of a cover, a clamping member comprising a pair of hollow hemispherical elements between which the upper edge of said cover is adapted to be inserted when folded into plaits, sufficient room being provided between and within said clamping members for the plaited edge of said cover, a ring form hanger member having depending hooks thereon, a connection between said clamping members and said hanging member comprising a vertical rod passing

through said clamping members, and means on said rod for actuating said clamping members toward each other to grasp the edge of said cover.

2. In a clothes hanger and protector, a hanger member in the form of a ring having depending hooks thereon, a cover clamp above the hanger member, and means including flexible members for connecting the hanger member to the cover clamping member, said cover clamping member consisting of a pair of hollow hemispherical elements into which the upper edge of said cover is adapted to be inserted by folding the latter into plaits, so that sufficient room is provided within the clamping member for the plaited edge of said cover, whereby said cover and flexible element are adapted to be collapsed for reducing the space occupied by the clothes hanger and protector, substantially as specified.

In testimony whereof I have signed my name to this specification in the presence of two subscribing witnesses.

LEONORE C. HILL.
